UNITED STATES PATENT OFFICE.

CARL G. OSTEMAN, OF BOSTON, MASSACHUSETTS, ASSIGNOR TO S. A. WOODS MACHINE COMPANY, OF BOSTON, MASSACHUSETTS, A CORPORATION OF MASSACHUSETTS.

BINDING AND WEIGHTING SYSTEM FOR BELT-DRIVES.

1,325,954.

Specification of Letters Patent. Patented Dec. 23, 1919.

Application filed October 27, 1919. Serial No. 333,465.

To all whom it may concern:

Be it known that I, CARL G. OSTEMAN, a citizen of the United States, and a resident of Boston, county of Suffolk, and State of Massachusetts, have invented an Improvement in Binding and Weighting Systems for Belt-Drives, of which the following description, in connection with the accompanying drawings, is a specification, like 10 characters on the drawings representing like parts.

This invention relates to a binding and weighting system for belt drives wherein it is desired to so tension the belts as to permit mechanisms to be run at high speed. The invention is applicable in particular to the drive of wood working machines, such as planers, matchers, molders and surfaces or the profiling attachments for such 20 machines. For the purpose of illustration I have herein shown an embodiment of the invention adapted to the drive for the surfacing heads of a molder.

My invention will best be understood by 25 reference to the following description taken in connection with the accompanying drawings, wherein I have shown in side elevation a portion of a molder with an embodiment of my invention applied thereto.

30 In the drawings, I have shown as much of a molder as is necessary to understand the application of my device to the drive thereof, the machine embodying upper and lower heads driven respectively by the belts 35 7 and 9 from the drive pulley 11. The belt 7 may embrace the pulley 11 in the ordinary manner and is tensioned by a top binder pulley or gravity binder 13 contacting exteriorly therewith. The upper run of the 40 belt 9 may contact with the drive pulley 11 throughout a suitable arc and, the bottom run being guided by the idler pulley 15, the belt is tensioned by binder pulley 17 contacting the runs on the drive pulley 11 and idler pulley 15 respectively. The pulleys 13 and 45 17 may be supported respectively on the swinging arms 19 and 21, pivoted on shaft 23.

50 The construction herein disclosed and which I am about to describe provides for counterbalancing a part of the weight of the pulley 13 so as to get the benefit of a pulley of large mass without the damage- 55 ing effect of a heavy weight on the belt and

also for supplying an efficient binding tension on the pulley 17. The mechanism is so organized that motion of any part is transmitted to the rest so that the inertia of the entire system is available to check 60 any dancing tendency of the binders.

In the form of invention herein illustrated I utilize a weighted lever 25 connected to the swinging arms 19 and 21 and herein a link 27 is connected to the arm 19 65 relatively close to the fulcrum so that the tendency of the weight to lift the pulley 13 is with comparatively small mechanical advantage, the leverage, in fact, being markedly in favor of the pulley. The lever 25 is 70 further connected by link 29 to the arm 21 and at a point relatively remote from the fulcrum thereof to exert a lifting tendency on the arm having a comparatively great 75 mechanical advantage which, in combination with the leverage provided in the weighted lever 25, will exert a strong tension on pulley 17 so as to counterbalance the same against gravity and exert a strong upward pull on the belt 9.

80 In the construction described the lever 25 is suspended by the two links 27 and 29 and to position the parts one of the links as 27 may be connected to the frame by a radius link 31, pivoted at 33. It will be seen that 85 the entire system floats about the point 33 and each part is adapted to transmit motion to the rest so that if there is any tendency for either of the pulleys to move, the entire system is set in motion and this motion is resisted by the inertia of the entire system. An effective binding tension is provided for belt 9 and a part of the weight of the top binder 13 is counterbalanced so 90 that a pulley of relatively great mass may 95 be used while comparatively small weight is exerted on the belt 7.

Link 29 may conveniently take the form of a rod swiveled in arm 21 and threaded into a block 35 pivoted in the end of lever 100 25. The rod is provided with a squared end 37 by which it may be turned to change the effective length thereof. Thus the proper amount of counterbalancing thrust may be exerted on link 27 and link or rod 29 then 105 adjusted to render the resulting pressure of the weight effective on pulley 17 properly to tension belt 9.

110 In the embodiment of the invention disclosed provision is made for shifting the

points of connection between arms 19 and 21 and links 27 and 29. Herein arm 19 is provided with a series of holes 39 by any one of which link 27 may be secured and the 5 arm 21 is provided with an elongated boss 41 having a series of openings by any one of which may be secured the block 43 in which rod 29 is swiveled.

Under certain circumstances it may be desired to drive one of the belts 7 and 9 in 10 the absence of the other or through an accident one of the belts may break. The mechanism herein disclosed will function properly in the absence of either belt. If 15 the belt 9 is removed the counterweight will fall to the floor swinging arm 21 up but the system will still be effective to counterbalance the pulley 13 on arm 19, the weight of pulley 21 then acting on lever 25 20 as on a lever of the second class, so called. If the top belt 7 is removed the arm 19 tends to fall and to limit its downward movement so that it may not crash into the drive pulley 11 a stop 40 may be provided 25 coöperating with a projecting end of radius link 31. The link comes in contact with this stop and supports the arm 19. The point of connection of the link 27 with the lever 25 then acts as a fixed fulcrum 30 about which the weight acts on arm 21 of the other binder.

I have described in detail the particular embodiment of my invention shown by way of example in the accompanying drawings. 35 It should be understood, however, that the particular design of motion transmitting means and the other mechanical details, while suitable for carrying out the purposes of my invention, are not essential to the principle involved. The invention may be embodied in various other mechanical forms and what I claim as new and desire to secure 40 by Letters Patent is:—

1. In combination with a pair of belts, 45 binder pulleys coöperating with the belts respectively, a weight for positioning the pulleys and means connecting pulleys and weight as a floating system wherein displacement of any part is resisted by the inertia of 50 all.

2. In combination with a pair of belts, an exteriorly disposed binder pulley for one, an interiorly disposed binder pulley for the other, a weight connected to the latter pulley 55 to thrust the same outwardly and to the former to counter-balance the same.

3. In combination with a pair of belts, a 60 swinging arm carrying a binder pulley contacting exteriorly with one belt, a second swinging arm carrying a binder pulley contacting interiorly with the other belt, a weight and means for connecting the weight to the first arm relatively close to the fulcrum and to the second remote from the 65 fulcrum.

4. In combination with a pair of belts, a swinging arm carrying a binder pulley contacting exteriorly with one belt, a second swinging arm carrying a binder pulley contacting interiorly with the other belt. 70 weight and means for connecting the weight to the first arm relatively close to the fulcrum and to the second remote from the fulcrum, the connections being adapted to transmit motion whereby movement of any part 75 is resisted by the inertia of the system.

5. In combination with a pair of belts, a swinging arm carrying a binder pulley contacting exteriorly with one belt, a second swinging arm carrying a binder pulley contacting interiorly with the other belt, a link 80 suspending a weighted lever from said first arm with relatively small mechanical advantage and a second link connecting said lever to the second arm with relatively great 85 mechanical advantage.

6. A combination as described in claim 5 wherein one of the links is adjustable.

7. In combination with a pair of belts, a swinging arm carrying a binder pulley contacting exteriorly with one belt, a second swinging arm carrying a binder pulley contacting interiorly with the other belt, a link suspending a weighted lever from said first arm with relatively small mechanical advantage, a common weighting means acting 90 on the first arm with comparatively small mechanical advantage to counter-balance the pulley and on the second with comparatively great mechanical advantage to tension the 95 corresponding belt and a stop limiting the inward movement of the first arm.

8. In combination with a pair of belts, an interiorly disposed binder pulley for one, an exteriorly disposed binder pulley for the other, a weighted arm and links suspending 105 said arm connected to said pulleys to tend to raise both of the same.

9. In combination with a pair of belts, an interiorly disposed binder pulley for one, an 110 exteriorly disposed binder pulley for the other, a weighted arm, links suspending said arm connected to said pulleys to tend to raise both of the same and a stop limiting upward movement of the link for said exteriorly disposed pulley.

10. In combination with a pair of belts, an interiorly disposed binder pulley for one, an exteriorly disposed binder pulley for the other, a weighted arm, links suspending said 120 arm connected to said pulleys to tend to raise both of the same and a radius link positioning one of the suspending links.

11. In combination with a pair of belts, an interiorly disposed binder pulley for one, an exteriorly disposed binder pulley for the other, a weighted arm, links suspending said arm connected to said pulleys to tend to raise both of the same, a radius link positioning 125 that suspending link which pertains 130

to the exteriorly disposed pulley and a stop coöoperating therewith to limit upward movement of the suspending link.

12. In combination with a pair of belts 5 an interiorly disposed binder pulley for one, an exteriorly disposed binder pulley for the other, a weighted arm, links suspending said arm and connected to said pulleys to tend to

raise both of the same and with provision for adjusting the connection to vary the effective lifting and means for positioning the linkage. 10

In testimony whereof, I have signed my name to this specification.

CARL G. OSTEMAN.
